UNITED STATES PATENT OFFICE.

RAY E. MANSON, OF ELYRIA, OHIO, ASSIGNOR TO THE DEAN ELECTRIC COMPANY, OF ELYRIA, OHIO, A CORPORATION OF OHIO.

TELEPHONE SYSTEM.

No. 918,566.

Specification of Letters Patent. Patented April 20, 1909.

Application filed April 18, 1907. Serial No. 869,014.

To all whom it may concern:

Be it known that E. RAY E. MANSON, a citizen of the United States, residing at Elyria, in the county of Lorain and State of Ohio, have invented certain new and useful Improvements in Telephone Systems, of which the following is a specification, reference being had therein to the accompanying drawings.

19 My invention relates to telephone systems, and has reference to the signaling means employed therein and the circuit connections therefor.

The invention comprises means for preventing a subscriber on a magneto line from ringing through the cord circuit at the exchange and operating the bell or bells on a connected line circuit. My circuits have the additional advantage of making it possible 20 to ring down the clearing out drop from one line when the other connected line circuit has a short circuit existing between its two sides, or when it has an extremely low resistance piece of apparatus connected across 25 the same.

In so-called magneto telephone systems, wherein the signaling currents are generated by hand machines worked by the subscribers, it is customary to bridge a high 30 wound annunciator magnet across each connecting cord circuit, so that at the conclusion of a conversation the subscribers may "ring off" and by actuating the bridge annunciator apprise the operator of their desire for disconnection. The bridged clearing out drop being high wound, a low resistance bridge across any part of the connected circuits will obviously take up a proportionately 35 large part of the ringing current, and if this bridge happens to be composed of one or more ringing branches, the result will be that one or more of the ringers will be actuated, while the high resistance bridge through the clearing out annunciator may not receive 40 current enough to signal the central office operator for disconnection.

Subsidiary objects and advantages will appear from the following detail description taken in connection with the accompanying 45 drawings.

My invention is illustrated in the accompanying drawings in which—

Figure 1 is a diagram showing a four-party line terminating in a switchboard jack in the

central office with a connecting cord circuit 55 having my present invention applied thereto. Fig. 2 is a diagram of a modified form of cord circuit also embodying the invention, and Fig. 3 is a simplified diagram intended to show the effect of a shunt or short circuit on 60 the ringing current.

Referring to the drawings, 1—2 is a subscriber's line extending from the central office to four substations, at each of which are located a hand generator G, a ringer Q, a receiver R, transmitter T, a switch hook H, and an induction coil I, the transmitter being supplied by a local battery b. The generator and ringer are in bridges across the line, both normally closed at the switch hook H, 70 but the generator branch normally open at contacts governed in its operation. Both the generator and ringer are preferably cut off when the receiver is taken from the hook, although this is not essential, provided the 75 ringers are wound sufficiently high. The ringers in the present case are supposed to be tuned and otherwise adjusted so that each one will respond to a particular frequency of ringing current only. At the central office 80 I provide four common generators G', G², G³ and G⁴ which produce currents of proper frequencies to selectively actuate the four bells on each line. Such an arrangement is known as a harmonic system and is selected 85 for illustration herein because without my present invention the current employed in ringing off is liable to actuate the low frequency ringers of such a harmonic system.

The line 1—2 is shown terminating in the 90 switchboard jack J associated with which I provide the usual line annunciator A, which is cut off in the jack upon the insertion of a plug P or P'. For the sake of simplicity in the diagram, I have shown portions of another subscriber's line at 3—4, terminating in a jack J' and having a line annunciator A'. This line also has a generator at the substation which I have marked G⁵, and which is employed for actuating 95 both the line annunciator A' and the clearing out annunciator A². This clearing out annunciator is bridged across the cord conductors which connect the plugs P and P'. The conductor which connects the tips of 100 the plugs is marked 5—6, and the conductor connecting the sleeves of the plugs is marked 7—8, each conductor being divided into two

portions by condensers C—C' for a purpose to be described. In order that the operator may communicate with the subscribers, I provide a telephone set O, which is adapted to be connected across the conductors 5—7 by means of a listening key K. For the purpose of ringing the wanted subscribers, I provide a ringing key K' connected on one side to the ground and on the other side to a set of selective keys k', k², k³ and k⁴, controlling the connection of the four selective generators to the key K'.

The annunciator A² is bridged across the cord circuit by means of conductors 9—10 and the gist of my invention lies in the manner in which this bridging is done. The conductor 9 is connected to the conductor 5 on the left hand side of the condenser C (see Fig. 1), while the conductor 10 is connected to the conductor 8 at the right hand side of its condenser C'. The use of these condensers in a magneto cord circuit is one of the distinguishing features of my invention, and the cross connection of the drop A² from one side of one condenser to the other side of the other condenser is another distinguishing feature. This drop is of very high impedance preferably wound to 500 ohms resistance and its connection across the cord circuits does not seem to unbalance the circuit conditions to any practical extent.

The operation of the system thus far described during the sequence of a connection and disconnection is as follows: Assuming that a call originates from line 1—2, one of the subscribers by operating his hand generator causes current to circulate in the line and to energize the annunciator magnet A. The falling of the shutter indicates to the operator that the line is calling, whereupon she inserts the answering plug P and by means of the key K connects her telephone set across the cord so as to ascertain the number wanted by the called subscriber. The plug P' is then inserted in the jack J' of the called line which we will assume to be any line equipped with the strong generator G'. The subscriber on the line 3—4 is called up by means of one of the generators G', G², etc., applied to the line through the keys K', k', k², etc. It will be noted that when either plug P or P' is inserted in a line jack J or J', the corresponding annunciator A or A' is disconnected in the jack, and at the same time the clearing out annunciator A² becomes bridged across the connected line circuits straddling the condensers. While ringing the wanted subscriber, the key K' opens the conductors 6 and 8 so that no ringing current passes back to affect the bridged annunciator, and thereafter the line and cord circuits remain intact, so that the clearing out drop is ready to respond to any magneto currents circulating therein.

When the subscribers have finished talking, therefore, one or both of them may send current from the corresponding generator or generators over the lines, and through the annunciator magnet A², throw down the drop. The course of such current from the line 1—2 may be traced as follows: generator G, 2, J, P, 5, 9, A², 10, C', 7, P, J, 1 and back to the generator. Similarly the path for current from the line 3—4 may be traced as follows: G², 4, J', P', 8, 10, A², 9, C, 6, P', J', 3 and back to the generator. For current through either line, it will be observed, a single condenser only is to be passed. For current from the line 1—2, the condenser C' is interposed in the clearing out circuit, while for current from the line 3—4 the condenser C is interposed in the clearing out circuit. For all lost current, however, which passes from either line to the other through the cord, both condensers C and C' must be passed through in series, and by properly adjusting the capacity of these condensers, the amount of leakage around the drop A² may be reduced to a negligible quantity. Upon perceiving that the shutter of the annunciator has fallen, the operator withdraws the plug P or P' and restores the parts to their original condition.

Fig. 2 shows a modification of the preceding circuit, in which both condensers C and C' are placed in the same side of the cord circuit. I do not consider this as good an arrangement as the other because of the tendency to unbalance the lines, but it is practicable and is illustrated because it is included in the scope of my invention and therefore falls under the claims I shall make herein.

Fig. 3 is a very condensed diagram illustrating the function of the condensers in preventing failure of the annunciator A² to operate due to a short circuit of low resistance in one of the lines. Quite obviously, the condensers are in series for currents in the following circuit. G, 1, 5, 6, 3, 4, 8, C', C, 7, 2, G. For current going to the annunciator, however, there is only one condenser in circuit as already shown. This prevention of short-circuiting is quite as important in its way as the prevention of ringing the bells in the connected lines. For example, the short circuit shown in Fig. 3 may be the branch through a low resistance series ringer on a short individual business line 3—4, while on the other hand the generator G may be located at one station on a long and heavily loaded country line having bridging instruments so that the amount of ringing current available for A² when the last subscriber on the line is ringing is very slight. Under such circumstances, the low wound series ringer in the absence of special provision such as I make will often shunt enough of the current

to make the clearing out drop inoperative. Again short circuits or crosses are not infrequent on country lines and upon aerial circuits in town. Such a short circuit with the shunt arrangement would absolutely prevent ringing off. With regard to the use in harmonic ringing systems, I may state that a 16 cycle or low frequency harmonic ringer is extremely sensitive and will operate on a hand generator current throughout a large range of frequencies and with very little current so that in practice the necessity has been strongly felt for more positive means to overcome this defect. Obviously, the inclusion 10 of the condensers whereby leakage through a short circuit is prevented, will prevent leakage through the connected ringers also and hence prevent their operation. The condensers C—C¹ may be of two m. f. each, but 15 are preferably of lower capacity so as to introduce a higher resistance to the ringing current. For talking purposes, the capacity may be reduced as low as one-fourth or one-fifth m. f. each without detriment. The 20 multiplied resistance afforded by the condensers in series together with the shunting effect of the drop A² itself, is sufficient to reduce the amount of current shuntage so that it will neither operate the 16 cycle ringer on 25 a connected line nor injuriously rob the drop magnet A².

It should be noted particularly that any given capacity used in the manner I have set forth will offer a much higher impedance to 30 the low frequency ringing currents than to the high frequency voice currents. Thus my arrangement has the advantage of cutting down the voice currents only slightly, and in fact imperceptibly; while for the low 35 frequency ringing currents, which give the most trouble, the impedance is very high. Furthermore, placing the two condensers in series for the ringing currents doubles this increased impedance with respect to the 40 bells connected in series with the same.

Having thus described a specific embodiment of my invention I may state that I am aware of various modifications that may be made in the system disclosed, all of which I 45 desire to include within the scope of my claims. Thus, I may in some cases substitute non-inductive resistance for the condensers, arranged so as to have less effect on the talking currents than on the ringing currents. Other arrangements of the condensers may be employed, or a larger number of condensers may be included in the circuit. Broadly stated, the gist of the invention lies 50 in the provision of means for differentiating the paths for signaling current and for talking current between subscribers. More specifically stated, it lies in the use of condensers so as to take advantage of their variation 55 and impedance for currents of varying frequencies.

Having thus described my invention what I claim and desire to secure by Letters Patent is—

1. In a signaling system, a source of signaling current, a device responsive to such 70 signaling current, conductors for electrically connecting such device to such source of signaling current, a second electrical path between such conductors, and means located on either side of the connection of such device to such conductors adapted to offer resistance to such signaling current varying inversely as the frequency of such current.

2. In a signaling system, a source of signaling current, a device responsive to such 80 signaling current, conductors for electrically connecting such device to such source of signaling current, a second electrical path between such conductors, and means located in one conductor on either side of the connection of such device to such conductors adapted to offer resistance to such signaling current varying inversely as the frequency of such current.

3. In a signaling system, a source of sig- 90 naling current, a device responsive to such signaling current, conductors for electrically connecting such device to such source of signaling current, a second electrical path between such conductors, and means located in one of the conductors between such device and such second electrical path adapted to offer resistance to such signaling current varying inversely as the frequency of such current.

4. In a signaling system, a source of signaling current, conductors leading from such source of current, an electrical path between such conductors, a device responsive to such 105 signaling current in bridge of such conductors between such source of current and such electrical path, and means located on either side of such bridge for directing sufficient current from such source through such bridge to operate such device regardless of the resistance of such electrical path.

5. In a signaling system, a source of signaling current, conductors leading from such source of current, an electrical path between such conductors, a device responsive to such 115 signaling current in bridge of such conductors between such source of current and such electrical path, and means located in one conductor on either side of such bridge for directing sufficient current from such source 120 through such bridge to operate such device regardless of the resistance of such electrical path.

6. In a signaling system, a source of signaling current, conductors leading from such 125 source of current, an electrical path between such conductors, a device responsive to such signaling current in bridge of such conductors between such source of current and such electrical path, and means located in one of

- the conductors between such device and such electrical path for directing sufficient current from such source through such bridge to operate such device regardless of the resistance of such electrical path.
7. In a signaling system, a source of signaling current, conductors leading from such source of current, an electrical path between such conductors, a device responsive to such signaling current in bridge of such conductors between such source of current and such electrical path, and condensers so located in the conductors that current flowing from such source through such device will flow through one of such condensers and current flowing from such source through such electrical path will flow through a second of such condensers.
8. In a signaling system, a source of signaling current, conductors leading from such source of current, an electrical path between such conductors, a device responsive to such signaling current in bridge of such conductors between such source of current and such electrical path, and two condensers so located in the circuits thus formed that current flowing from such source through such device will flow through one of such condensers and current flowing from such source through such electrical path will flow through both of such condensers.
9. In a signaling system, two conductors adapted to connect two terminal stations and an intermediate station, a source of signaling current adapted to be connected to such conductors at each station, a signal-receiving device normally connected to such conductors at each station, and means located in such conductors for preventing either terminal source of current operating the other terminal signal-receiving device without preventing the operation by either terminal source of current of the intermediate signal-receiving device.
10. In a signaling system, two conductors adapted to connect two terminal stations and an intermediate station, a source of signaling current adapted to be connected to such conductors at each station, a signal-receiving device normally connected to such conductors at each station, and means located in one of such conductors on either side of the intermediate device for preventing either terminal source of current operating the other terminal signal-receiving device without preventing the operation by either terminal source of current of the intermediate signal-receiving device.
11. In a signaling system, two conductors adapted to connect two terminal stations and an intermediate station, a source of signaling current adapted to be connected to such conductors at each station, a signal-receiving device normally connected to such conductors at each station, and means located in one of such conductors on either side of the intermediate device for preventing either terminal source of current operating the other terminal signal-receiving device without preventing the operation by either terminal source of current of the intermediate signal-receiving device.
12. In a combined signaling and telephone system, a circuit adapted to connect two terminal stations and an intermediate station, a source of signaling current adapted to be connected to such circuit at each station, a signal-receiving device normally connected to such circuit at each station, apparatus at each station adapted to transmit and receive voice currents, means in such circuit on each side of the intermediate device for permitting either terminal source of current to operate such intermediate device, such means adapted to prevent either terminal source of current operating the other terminal signal-receiving device without materially impeding the flow of voice currents in such circuit between the terminal stations.
13. In a combined signaling and telephone system, a circuit adapted to connect two terminal stations and an intermediate station, a source of signaling current adapted to be connected to such circuit at each station, a signal-receiving device normally connected to such circuit at each station, apparatus at each station adapted to transmit and receive voice currents, means in one conductor of such circuit on either side of the intermediate device for permitting either terminal source of current to operate such intermediate device, such means adapted to prevent either terminal source of current operating the other terminal signal-receiving device without materially impeding the flow of voice current in such circuit between such stations.
14. In a combined signaling and telephone system, two conductors adapted to connect two terminal stations and an intermediate station, a source of signaling current adapted to be connected to such conductors at each station, a signal-receiving device normally connected to such conductors at each station, apparatus at each station adapted to transmit and receive voice currents, and means located in one of such conductors for preventing one terminal source of current operating the other terminal signal-receiving device without materially impeding the flow of voice currents in the circuit between the terminal stations and without preventing the operation of the intermediate device from such terminal source of current.

In testimony whereof I affix my signature
in presence of two witnesses,

RAY H. MANSON.
